UNITED STATES PATENT OFFICE.

AARON T. PICKETT, OF DETROIT, MICHIGAN.

ELECTRIC SIGNAL ALARM.

1,425,279.

Specification of Letters Patent. Patented Aug. 8, 1922.

Application filed November 12, 1919. Serial No. 337,595.

To all whom it may concern:

Be it known that I, AARON T. PICKETT, citizen of the United States, residing at Detroit, county of Wayne, State of Michigan, have invented a certain new and useful Improvement in Electric Signal Alarms, and declare the following to be a full, clear, and exact description of the same, such as will enable others skilled in the art to which it pertains to make and use the same, reference being had to the accompanying drawings, which form a part of this specification.

My invention relates to an electric signaling device and is particularly designed for use in banking offices, or the like, that assistance may be called in the event of a so-called "hold up" or attempted robbery.

The object of the present invention is to provide means whereby a bank teller or other clerk may secretly signal for assistance even though he may be required to "hold up" his hands under threat of losing his life.

A further object is to provide for sounding a continuous alarm, or of displaying a danger or "red" light, or both which will be constant until assistance is secured even though the party sending in the warning signal may not be in uninterrupted control of the signaling means.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the accompanying drawings forming part of this specification:—

Figure 1 is a diagrammatic and perspective view showing a bank teller's "cage," the signaling apparatus and wiring.

Figure 2 is an elevation of a device comprising an electromagnet and means controlled thereby for closing an electric circuit.

Figure 3 is a vertical sectional view of the device taken on or about line 3—3 of

Figure 2.

Figure 4 is a plan view of a floor-push to close the circuit through the electromagnet.

Figure 5 is a vertical cross-sectional view of the floor-push.

Referring now to the letters of reference placed upon the drawings:—

A, denotes a bank teller's cage. B, indicates a floor-push having a plurality of resilient radial fingers B' which are adapted when compressed to close a circuit through the plate C insulated therefrom by a disc D.

E, designates a battery and F, an electromagnet. G, is the armature of the magnet and H a spring for separating the armature from the core of the magnet when the latter is demagnetized.

I, indicates a spring actuated swinging arm supported on the stub-shaft I', journaled in the frame of the magnet, having one end bent to form a detent I², which overlaps the side wall of the armature when the latter is in its normal or released relation to the magnet and when the magnet is energized the armature G is moved from the position illustrated in Figure 1 of the drawing and withdrawn from engagement with the detent I² which is thereby released for closing the lowermost circuit.

J, is a spring coiled on the stub shaft I' one end of which engages a pin J', projecting from the frame of the magnet,—the other end engages a lever arm I³ secured to the end of the stub shaft.

K, denotes a signal bell and L a signal light which may be located at distant points,—as for example the outside of the banking office, at police headquarters or both.

M, denotes a battery in the circuit which includes the bell and signal light. This circuit is closed,—causing a continuous ringing of the bell and display of the signal light—by the release of the spring actuated swinging arm I, which is normally held in an "open" position by the armature G, of the magnet F, engaging the off-set end or detent I², of the swinging arm. The spring actuated swinging arm is released by the movement of the armature G, upon energizing the magnets F by closing the circuit through the floor push B and battery E. The bell will then ring continuously and the signal light will burn uninterruptedly until the circuit through the battery M is again opened by the manual return of the swinging arm I to its initial position, in which position it is held by the armature G

until the latter is again released through energizing the magnet F by closing the circuit through the floor push as previously explained.

5 The lever arm I³ is fitted with a knob I⁴, for convenience in manually returning the swinging arm to its initial position.

Having thus described my invention what I claim is:—

- 10 1. In a device of the character described, including a magnet frame, an electro-magnet having an armature, a spring controlled arm pivotally mounted on the frame and adapted to normally overlap the armature of the electro-magnet and be thereby restrained against action of the spring, said electro-magnet adapted to be energized to carry the armature out of the path of the arm to release the latter and thereby close a circuit to actuate an alarm, and an operating arm connected with the swinging arm whereby the swinging arm may be manually returned to its initial overlapping relation with the armature when the magnet is deenergized.
- 15 2. In a device of the character described, including a magnet frame, an electro-magnet having an armature, a spring controlled arm pivotally mounted at the upper end on the frame and arranged to swing at right angles to the arm and provided with a detent at the lower end adapted to normally overlap the armature of the electro-magnet and be thereby restrained against the action of the spring, said electro-magnet adapted to be energized to shift the armature away from the detent of the arm and
- 20
- 25
- 30

thereby release the latter to effect a closing 35 of a circuit and a consequent actuation of an alarm.

3. In a device of the character described, including a magnet frame, an electro-magnet having an armature, a spring controlled 40 arm pivotally mounted on the frame and adapted to normally overlap the armature of the electro-magnet and be thereby restrained against action of the spring, and said electro-magnet adapted to be energized to carry 45 the armature out of the path of the arm to release the latter and thereby close a circuit to actuate an alarm, and an operating arm connected with the swinging arm whereby the swinging arm may be manually returned 50 to its initial overlapping relation with the armature when the magnet is deenergized.

4. In a device of the character described, an electro-magnet having an armature pivoted at the top and provided thereat with an angularly related spring arm, a swinging arm pivoted at its upper end and arranged to swing at right angles to the armature and provided at the lower end with a detent arranged to engage the armature, and an operating arm connected with the swinging arm. 55 60

In testimony whereof, I sign this specification in the presence of two witnesses.

AARON T. PICKETT.
